SHAVING MACHINE

John C. Garand, Springfield, Mass.

Application November 18, 1942, Serial No. 466,090

9 Claims. (Cl. 90—11)

(Granted under the act of March 3, 1883, as
amended April 30, 1928; 370 O. G. 757)

The invention described herein may be manufactured and used by or for the Government for governmental purposes, without the payment to me of any royalty thereon.

This invention relates to a shaving fixture for producing, on a helical lead, the finish cut on the locking lugs of a receiver of a firearm.

The headspace tolerances of firearms are held within very close limits. This is necessarily so because the high breech pressures involved in modern firearms require that exceptionally close tolerances be maintained at such a critical point. On most firearms some form of locking lugs is provided on the bolt which engage suitable locking surfaces in the receiver to withstand these high breech pressures. Even with modern machine tool equipment, it is extremely difficult to hold the very close tolerances required in the headspacing of a firearm.

It is important that the receiver locking surfaces be cut true and smooth in order that the locking lugs of the bolt will bear squarely against the locking surfaces in the receiver. The locking surfaces in the receiver are generally rough formed first in a machine tool. As the locking lugs are usually inaccessibly located within the receiver, finish machining of these lugs by conventional machine tool methods is very difficult. The difficulty is increased by the fact that such surfaces should generally be somewhat helical.

Accordingly it is an object of this invention to provide a shaving fixture for making highly accurate cuts on relatively inaccessible surfaces within a metal body.

Another object of this invention is to provide a shaving fixture for removing metal from the locking surfaces of a firearm receiver on a helical lead to produce smoothly finished highly accurate locking surfaces.

A particular object of this invention is to provide a shaving fixture which will produce a finished locking surface on the locking lugs of a receiver for a firearm such as disclosed in my prior U. S. Patent No. 1,892,141.

The specific nature of the invention as well as other objects and advantages thereof will clearly appear from a description of a preferred embodiment as shown in the accompanying drawings in which:

Fig. 1 is a longitudinal sectional view of the shaving machine as shown in Fig. 2.

Fig. 2 is a side elevational view of the shaving machine.

Fig. 3 is a left end elevational view of Fig. 2.

Fig. 4 is cross sectional view of Fig. 1 taken along the plane 4—4.

Fig. 5 is a fragmentary view of a firearm receiver showing the bolt locking lugs. The receiver is shown in this view turned in the opposite direction from the position it occupies when placed on the machine.

In Fig. 1 there is shown in assembled relation a shaving fixture embodying this invention. A U-shaped base 1 has two upwardly projecting arms 2 and 3. The arm 2 is somewhat longer and wider than the arm 3. Near the top of the arm 2 a transverse hole 4 is provided to receive a shaft which will be presently described. An arcuate surface 5 is formed at the top of the arm 2 on a radius swung from the axis of the hole 4. Short longitudinal indexing graduations 6 extending rearwardly from the inner face 7 of the arm 2 are provided on the arcuate surface 5 on the top of arm 2 (Fig. 2).

Threaded holes 8 and 9 are centrally provided in the bottoms of the arms 2 and 3 respectively. A rectangular base plate 11 is secured to the base 1 by the screws 12 and 13 which are screwed into the threaded holes 8 and 9.

A U-shaped end plate 14 is secured to the arm 3 of the base 1 by a screw 23 which is inserted through a hole 22 in the end plate 14 and into a suitably threaded hole 10 in the arm 3. The end plate 14 is also secured to base plate 11 by the screws 24 and 25 threadably inserted in suitable holes provided on the bottom edge of the end plate 14 and the base 11.

The arm 15 of the U-shaped end plate 14 is slightly longer than the arm 16 as shown in Fig. 3. Steps 17 and 18 are formed on the inside edge of the U-shaped recess 19 on the arms 15 and 16 respectively. Near the bottom edge of the U-shaped recess 19 there is provided a transverse hole 20 in arm 15 to receive a stop 26.

The stop 26 is a bolt-like member having a shaft portion 27 and a cylindrical head 28. The shaft portion is inserted into the hole 20 so that the cylindrical head 28 faces the recess 19. Directly opposite the hole 20 there is provided a transverse hole 21 in the arm 16. The hole 21 is suitably counterbored to receive a plunger 29. The plunger 29 is biased outwardly into the recess 19 by a spring 31 provided in back of the plunger in the counterbored hole 21.

An integral shoulder 30 provided on the plunger 29 strikes the bottom of the counterbored hole 21 thereby preventing the plunger 29 from passing out of the hole 21. A screw 32 retains the spring and plunger within the hole 21.

55 A shaft 33 (Fig. 1) is inserted in the hole 4 in

the arm 2. Approximately in the center of shaft 33, there is provided an enlarged portion 34. As viewed in Fig. 1 the left shoulder of the enlarged portion 34 is cut on a helical lead to form a helical cam surface 35. A cutter 78 which will be described is mounted on the shaft portion adjacent the cam surface 35. The end 36 of shaft 33 is chamfered to facilitate mounting the cutter 78. To the right of the enlarged portion 34 there is provided a suitably turned portion 37 of somewhat smaller diameter than the enlarged portion 34 to receive a ratchet 40.

The ratchet 40 is a cylindrical member provided with an integral exterior threaded axially projecting hub 41. An axial hole 42 is provided in the ratchet to mount the ratchet on the portion 37 of shaft 33. Evenly spaced horizontal serrations 43 (Fig. 2) are provided on the periphery of the ratchet 40. On the face of the ratchet 40 adjacent the threaded hub 41 there are provided equally spaced slightly raised bearing surfaces 44 (Fig. 3). On the opposite face of ratchet 40 a recess 45 is provided (Fig. 1). The ratchet 40 is placed on the shaft 33 with the threaded hub 41 adjacent the right side of the enlarged portion 34 of the shaft 33.

The remaining portion of the shaft adjacent the portion 37 of the shaft 33 is somewhat smaller in diameter to pass through the hole 4. The end 38 of shaft 33 is suitably threaded to receive a nut 46. Adjacent the recess 45 of the ratchet 40 a spring washer 39 is mounted on shaft 33 and adjacent the washer 39 there is placed a collar 57. The collar 57 is a thin cylindrical washer-like member having a reduced diameter end portion 58 to receive a lever 47 which will be presently described. A collar 59 similar to the collar 57, comprising a head 60 and a reduced diameter end portion 61 is mounted on the shaft 33 with the portion 61 adjacent portion 58 of the collar 57. A key 62 inserted into a suitable key slot in shaft 33 and the collar 59 secures the collar 59 in locked relation to shaft 33.

Two oppositely disposed flat milled surfaces (Fig. 4) 63 and 64 are centrally provided on that portion of shaft 33 which is mounted in the arm 2. In the arm 2 two oppositely disposed set screws 65 and 66 are inserted in a suitably threaded transverse hole 67 in the arm 2 which just clears the bottom of the hole 4. The set screws 65 and 66 thus may bear against the flat milled surfaces 63 and 64 respectively. The shaft 33 is inserted in the hole 4 in the arm 2 with head 60 of collar 59 adjacent face 7 of the arm 2 and is secured to the arm 2 by the nut 46. The head 60 abuts the shoulder of shaft portion 37 thereby acting as a stop for the shaft 33.

The lever 47 (Fig. 4) comprises a handle portion 48 and an integral downwardly projecting inverted V-shaped section 49. The end of the section 49 is bifurcated to form two downwardly projecting lugs 50 and 51. An integral outwardly projecting lug 53 (Fig. 1) is provided which extends across the lower face of the inverted V section 49. A longitudinal rectangular slot 54 is provided in the top of the projecting lug 53. A hole 55 is provided in the member 49 to mount the lever 47 on the reduced diameter portions 58 and 61 of the collars 57 and 59 respectively mounted on the shaft 33. Sufficient clearance is provided between the collars 57 and 59 to permit the lever 47 to be rotated freely about the collars 57 and 59. The lugs 50 and 51 limit the rotational movement of lever 47 in either direction by engagement with base 1.

Two pawls 68 and 69 are centrally mounted within the slot 54 by a pin 73 which is inserted in a suitable transverse hole in lever 47 passing through the slot 54 and the transverse holes 90 and 91 respectively provided near the lower edge of one corner of each of the pawls 68 and 69. Upwardly inclined arcuate surfaces 92 and 93 are respectively provided near the hole 70 on the pawls 68 and 69. The corner opposite the arcuate surface 71 is rectangularly formed. A sharp projection 72 is provided on both pawls 68 and 69 by the juncture of the upwardly inclined arcuate surfaces 92 and 93 and the opposite side. Two holes 74 and 75 are provided in the base of each pawl 68 and 69 to receive springs 76 and 77 respectively which are mounted in recesses 56 in lever extension 53 and act to bias the pawls upwardly.

A pin 88 (Fig. 1) is inserted in a transverse hole 10 in the arm 3. The pin 88 has a forwardly projecting portion 89 of smaller diameter which extends under the ratchet 40. The pin 88 is slightly offset with respect to the vertical position of the lever 47 and is positioned in the arm 3 in such a manner that the arcuate surface 71 on the pawls 68 and 69 bears against the forwardly projecting portion 89 of the pin 88. The pin 88 being offset with respect to the vertical central position of the lever 47 is thus eccentric with respect to the pawls 68 and 69 as the pin 73 about which the pawls pivot is on the same center of rotation as that of lever 47. Therefore one pawl will be closer to the pin 88 than the other and one of the pawls will move the ratchet 40 farther than the other. Thus reciprocation of the lever 47 gradually advances the ratchet 40 in a counterclockwise direction as viewed in Fig. 4. This will be described in more detail later.

A shaving cutter 78 of suitable tool steel is slidably mounted on the shaft 33. The cutter 78 (Figs. 2 and 3) comprises a tubular body 79 and a head 80. On the right hand end of the head 80 there is provided a helical surface corresponding to the helical surface provided on the cam 35. Two oppositely disposed integrally formed lugs 81 and 82 are provided on the head 80 of the cutter 78. The left hand edges of the lugs 81 and 82 as viewed in Fig. 2 are suitably ground to form the cutting edges of the cutter 78. It is of course possible in the interest of reducing the amount of tool steel required, to form the body of the cutter of ordinary steel and to weld or braze the lugs 81 and 82 of suitable tool steel to the body of the cutter. There is provided a threaded hole 83 in the projecting lug 81 in which is screwed a handle 86. The handle 86 is prevented from turning by a lock nut 87. Lugs 84 and 85 are provided on handle 86 which contact suitable stops 98 (Figs. 2 and 3) on the upstanding arms 15 and 16 to limit rotation of the handle 86.

To shave the locking surfaces on the interior of a receiver 94 (Fig. 5) the cutter 78 is inserted within the receiver. The proportions of cutter 78 are such as to render it readily insertable in the cartridge loading and/or ejection opening customarily provided in firearm receivers. The cutter and receiver are then placed over the shaft 33 with the receiver turned end for end from its position shown in Fig. 5 and the threaded end of the receiver brought to bear against the threaded hub 41 of the ratchet 40. The ratchet 40 is then turned in a counter-clockwise direction as viewed in Fig. 4 to engage threads 95 in the end of the receiver. The lever 47 is however

first rotated in a counter-clockwise direction as viewed in Fig. 4 as far as it will go to bring the pawl 69 against the portion 89 of pin 88 and thus out of engagement with the ratchet 40. The pawl 68 will of course slide over the serrated surface on the ratchet 40 as the ratchet is screwed into the receiver. Hence the receiver 94 is drawn towards the ratchet until the lugs 82 and 81 on the cutter 78 contact the locking lugs 96 and 97 respectively within the receiver 94. The receiver is held against rotation between stop 26 and spring biased plunger 29. It should be mentioned that prior to shaving the locking lugs within the receiver, the device should be adjusted by means of the adjusting screws 65 and 66 so that when operating the fixture the locking lugs 96 and 97 will be cut to the proper finished dimension. This is readily accomplished by loosening the adjusting screws 65 and 66 and manually rotating the shaft 33 slightly. This movement simultaneously rotates the cam 35 and moves the adjacent cutter 78 to either the right or left along the shaft 33 depending whether the shaft was rotated in a clockwise or counter-clockwise direction. When the cutting edges of the lugs 81 and 82 are at the correct headspace distance from the face adjacent the hub 41 of the ratchet 40 as determined by a suitable gauge the shaft is locked in this position by again tightening the screws 65 and 66.

The cutter is first placed in position so that the cutting edges of the lugs 81 and 82 just contact the locking lugs 96 and 97 respectively within the receiver 94. The lever 47 is then rotated in a counterclockwise direction as viewed in Fig. 4 until the lug 50 contacts the base 1. When the lever 47 is moved in this direction the pawl 68 under the bias of spring 76 engages one of the serrations 43 on the ratchet 40 and rotates the ratchet 40 a distance equivalent to about two notches in a corresponding direction. Lug 50 engages base 1 to limit this movement. When the ratchet has been advanced this amount, the pawl 68 strikes the forwardly projecting end 89 of pin 88 and is rocked out of engagement with the serration 43 thereby stopping further rotation of the ratchet. The pawl 69 rides over the serrations 43 without engagement therein when the lever 47 is rotated in this direction. This brings the receiver ahead a slight amount and into position for the first shaving cut. The handle 86 is then rotated in a clockwise direction as viewed in Fig. 3. This movement passes the cutting edges of lugs 81 and 82 across the face of the locking lugs in the receiver, thereby shaving off a small amount of material. The engagement of lug 85 with stop 98 limits this movement.

The lever 47 is then rotated in a clockwise direction as viewed in Fig. 4 until the lug 51 strikes the base 1. When the lever 47 is pushed in a clockwise direction, the pawl 68 is pressed out of engagement with the serrations 43 due to the shape of the engaging surfaces and the pawl 69 engages one of these serrations 43 and backs off the ratchet one serration. When the ratchet has been backed off a distance equivalent to one notch, the pawl 69 strikes the portion 89 of pin 88 thus limiting further rotation of the ratchet 40. At this point the lug 51 strikes the base 1 to prevent injury to the pawls. The cutter 78 is then rotated in a counterclockwise direction by the handle 85 to be in position for making another shaving cut. When the lever 47 is rotated clockwise and backs off the receiver slightly, the cutting edges of the cutter do not contact the locking lugs on the return stroke and hence do

not dull these cutting edges. The lever 47 is then moved in a counterclockwise direction and simultaneously the pawl 68 engages the ratchet 40 and advances the receiver forward two notches so that when the handle 86 of the cutter 78 is rotated to shave off a small amount of metal, the receiver will have been advanced one notch. This operation is repeated until the end of receiver 94 has been brought into bearing contact with the surfaces 44 of ratchet 40 at which point the locking lugs will have been shaved to the desired dimension.

By the location of the pin 88 offset with respect to the vertical position of the lever 47 it is possible for the pawls to engage the ratchet in the manner described above, i. e., one pawl advancing the receiver 94 two notches into the cutters and the other pawl backing off the receiver 94 one notch when the lever is rotated in the opposite direction. The operation of moving the lever 47 and the handle 86 of the cutter 78 is repeated until the face of the receiver 94 abuts the adjoining faces 44 of the ratchet 40. At this point the proper amount of metal has been removed from the locking lugs and the receiver is removed from the fixture by unscrewing the ratchet 40 manually and withdrawing the receiver and cutter from the shaft 33. The receiver is held in a fixed position while on the fixture by the spring biased plunger 29 which bears against one side of the receiver and holds it properly located.

I claim:

1. A machine for shaving interior surfaces of a hollow work piece having a threaded portion comprising a base, means on said base arranged to engage the threaded portion of the work piece, a tool body rotatably mounted on said base and arranged to extend within said work piece, a cutter mounted on said tool body, means for rotating said tool body, and means for rotating said first mentioned means to advance the work piece with respect to the cutter by means of the threaded engagement between the work piece and said first mentioned means.

2. A machine for helically shaving interior surfaces of a hollow work piece comprising a base, threaded means on said base arranged to engage and support a work piece, a tool body rotatably mounted on said base and arranged to extend within said work piece, a cutter mounted on said tool body, a helical surface on the end of said tool body, a member fixed on said base having a helical surface arranged to lie in abutment with said tool body helical surface, means for rotating said tool body, and means for rotating said threaded means to advance the work piece with respect to the cutter.

3. A shaving machine comprising a base, a bracket, a shaft secured in said bracket, a threaded collar on said shaft arranged to threadably engage a work piece and secure it in surrounding relation to said shaft, a cutter having a hollow cylindrical body arranged to be mounted on said shaft within the work piece, means for rotating said cutter, and means for rotating said collar whereby the work piece may be advanced with respect to said cutter.

4. A shaving machine comprising a base, a bracket, a shaft secured in said bracket, a threaded collar on said shaft arranged to threadably engage a work piece and secure it in surrounding relation to said shaft, a cutter having a hollow cylindrical body arranged to be mounted on said shaft within the work piece, means for reciprocating said cutter about said shaft, a lever

mounted on said shaft for limited pivotal movement thereon, and ratchet means interconnecting said lever and said collar whereby pivotal reciprocation of said lever rotates said collar and advances the work piece with respect to the cutter. 5

5. A helical shaving machine comprising a base, a bracket, a shaft secured in said bracket, a threaded collar on said shaft arranged to threadably engage a work piece and secure it in surrounding relation to said shaft, a cutter having a hollow cylindrical body arranged to be mounted on said shaft within the work piece, a first helical surface on the end of said cutter, a second helical surface on said shaft in abutment with said first helical surface, means for rotating said cutter, and means for rotating said collar whereby the work piece may be advanced with respect to said cutter. 10

6. A shaving machine comprising a base, a bracket, a shaft secured in said bracket, a threaded collar on said shaft arranged to threadably engage a work piece and secure it in surrounding relation to said shaft, a cutter having a hollow cylindrical body arranged to be mounted on said shaft within the work piece, means for reciprocating said cutter about said shaft, a lever mounted on said shaft for limited pivotal movement thereon, a plurality of serrations in the periphery of said collar, a pair of pawls on said lever resiliently engageable in said serrations, each pawl respectively operative to rotate said collar in opposite directions, and pawl disengaging means nonconcentrically located with respect to said pawls whereby reciprocation of said lever produces a net rotation of said collar to advance the work piece with respect to the cutter. 15

7. A helical shaving machine comprising a base, a bracket, a shaft secured in said bracket, a threaded collar on said shaft arranged to threadably engage a work piece and secure it in surrounding relation to said shaft, a cutter having a hollow cylindrical body arranged to be mounted on said shaft within the work piece, a first helical surface on the end of said cutter, a second helical surface on said shaft in abutment with said first helical surface, means for reciprocating said cutter about said shaft, a lever mounted on said shaft for limited pivotal movement thereon, a plurality of serrations on the periphery of said collar, a pair of pawls on said lever resiliently engageable in said serrations, each pawl respectively operative to rotate said collar in opposite directions, and pawl disengaging means nonconcentrically located with respect to said pawls whereby reciprocation of said lever produces a net rotation of said collar to advance the work piece with respect to the cutter. 20

8. A shaving machine as in claim 5 plus means for limiting the advance of the work piece with respect to the cutter and means for adjusting the radial position of said second helical surface thereby determining the depth of the shaving operation. 25

9. A shaving machine as in claim 7 plus means for limiting the advance of the work piece with respect to the cutter and means for adjusting the radial position of said second helical surface thereby determining the depth of the shaving operation. 30
